[57] CLAIM

The ornamental design for a squirting water toy, substantially as shown and described.

DESCRIPTION

FIG. 1 is a top plan view of a squirting water toy showing our new design;

FIG. 2 is a side elevational view thereof, the side opposite being substantially a mirror image thereof;

FIG. 3 is a front elevational view thereof; and

FIG. 4 is a rear elevational view thereof.
